UNITED STATES PATENT OFFICE.

WILLARD M. McEWEN, OF CHICAGO, ILLINOIS.

CEILING-FAN.

1,287,059.

Specification of Letters Patent. Patented Dec. 10, 1918.

Application filed November 29, 1916. Serial No. 134,037.

To all whom it may concern:

Be it known that I, WILLARD M. McEWEN, a citizen of the United States of America, and a resident of Chicago, county of Cook, 5 and State of Illinois, have invented certain new and useful Improvements in Ceiling-Fans, of which the following is a specification.

The main objects of this invention are to 10 provide an improved form of air circulating device constructed so as to be tilted or oscillated simultaneously in two transverse planes in a similar manner to that shown in my prior Patent No. 1,214,198, granted January 30, 1917, to provide an improved form 15 of mounting for the device; and to provide an air circulating device of this kind which is particularly suitable for use as a ceiling fan.

20 An illustrative embodiment of this invention is shown in the accompanying drawings, in which:

Figure 1 is a transverse sectional elevation of the improved air circulating device, the 25 same being shown as suspended from the ceiling.

Fig. 2 is a side elevation of the same.

Fig. 3 is a bottom plan of the same.

Fig. 4 is an enlarged detail, partly sectional, of the crank member and its reduction gearing, the section being viewed from the plane of the line A—A of Fig. 5.

Fig. 5 is a sectional elevation of the same.

The air circulating device herein shown 35 and described is of the type wherein means are provided for positively tilting the blower mechanism in one plane, whereby it will oscillate in a transverse plane by virtue of the gyratory forces which become active when 40 the blower mechanism is tilted in said first mentioned plane.

In the construction herein shown the main supporting frame is an annular member 1 of U-shaped cross section within which a ring 45 member 2 is mounted on ball bearings 3, so that said ring member is free to rotate in its own plane and that of the supporting member 1.

Blower mechanism 4, which may be of any 50 of the usual constructions including a motor (not shown) and fan blades 5, is tiltably mounted on the ring member 2 by means of trunnions 6 and 7. The trunnions are secured to the motor casing 8 and seated in 55 bearings 9 and 10 integrally formed on the ring member 2, whereby the blower mecha-

nism is pivotally supported so as to be tilted in a plane transverse to the axis of said trunnions and to the plane of the ring member 2.

The tilting of the blower mechanism may be effected by any means which may be found suitable for that purpose. That illustrated in the drawings is in the nature of a crank member comprising a ball member 11 carried by a shank or arm 12 eccentrically secured on a disk 13. The disk 13 is connected to the motor shaft 14 through the medium of suitable reduction gearing 15 housed within the disk, as shown in Figs. 4 and 5.

In order that the crank member will effect a straight back and forth tilting, the ball member 11 is arranged to travel in a guideway 16 formed in ring member 2 in a longitudinally disposed position.

This form of mounting is particularly suitable for ceiling fans, and to that end a plate 17 is integrally formed on the annular member 1, which may be secured to the ceiling so as to suspend the frame in a vertically disposed position. The fan being mounted on one side of the center of the ring member 2 it is necessary to provide a counterweight in order to insure the fan being normally held with the motor axis vertical and the fan blades down. This is readily accomplished by casting a web 18 on the ring member 2 in opposed relation to the fan blades 5, and of suitable weight to counterbalance the weight of that part of the blower mechanism which is on the opposite side of the axis of said ring.

A diagrammatic arrangement of electrical conducting means is shown in the drawings, which embodies a pair of slip rings 95 19 and 20 mounted on the ring member 2 in position to be engaged by a pair of brushes 21 and 22 mounted on the annular supporting member 1. The slip rings are connected to binding posts 23, from which 100 conductors 24 lead to the motor. The brushes are similarly connected with a source of electricity.

The operation of the device when used as a ceiling fan is as follows:

The rotation of the disk 13 causes the ball 11 and guideway 16 to coact to swing the fan back and forth in a vertical plane transverse to the plane of the supporting frame. This swinging or tilting of the rotating fan 110 causes the normally inactive gyratory forces inherent in the rotating fan to become ac-

tive. The ring 2 being free to rotate in the annular supporting member 1, these gyroscopic forces react and cause the blower mechanism to oscillate back and forth in a vertical plane transverse to that in which the mechanism is tilted initially.

Although but one specific embodiment of this invention has been herein shown and described, it will be understood that numerous details of the construction shown may be altered or omitted, without departing from the spirit of this invention as defined by the following claims.

I claim:

- 15 1. An air circulating device, comprising an annular supporting member, a ring member mounted on said supporting member so as to be free to rotate in the plane thereof, blower mechanism located wholly within 20 said ring member and trunnioned thereon so as to be capable of tilting in a plane transverse to the plane of said ring member, and coacting means on said blower mechanism and ring member positively driven by said 25 blower mechanism for tilting said blower mechanism, whereby gyroscopic forces react to cause said blower mechanism to oscillate with said ring member on said supporting member.
- 30 2. In a ceiling fan, the combination of an annular member of U-shaped cross section providing an annular groove in the inner face thereof, a plate rigidly connected to and suspending said member in a vertically disposed position, a ring member supported within said annular member so as to freely rotate in the plane of said annular member, blower mechanism located wholly within 35
- 25

said ring member and trunnioned thereon so as to tilt in a vertical plane transverse to the plane of rotation of said ring member, and coacting means on said blower mechanism and said ring member positively driven by said blower mechanism and adapted to tilt said blower mechanism in said transverse vertical plane, whereby gyroscopic forces react to oscillate said blower mechanism vertically in the plane of said annular member.

3. In a ceiling fan, the combination of an annular member of U-shaped cross section providing an annular groove in the inner face thereof, a plate rigidly connected to and suspending said member in a vertically disposed position, a ring member supported with- 55 in said annular groove so as to freely rotate in the plane of said annular member, blower mechanism located wholly within said ring member and trunnioned thereon so as to tilt in a vertical plane transverse to the plane of rotation of said ring member, coacting means on said blower mechanism and said ring member positively driven by said blower mechanism and adapted to tilt said blower mechanism in said transverse vertical plane, whereby gyroscopic forces react to oscillate said blower mechanism vertically in the plane of said annular member, and a counterweight carried by said ring member adapted to normally urge said ring member 60 into position to maintain said blower mechanism in a vertically disposed position.

Signed at Chicago this 27th day of November, 1916.

WILLARD M. McEWEN.
